UNITED STATES PATENT OFFICE.

CARL E. SJOMAN, OF LAKE PARK, MINNESOTA.

QUICK-SHIFTING ANTIRATTLING THILL-COUPLING.

No. 902,614.

Specification of Letters Patent.

Patented Nov. 3, 1908.

Application filed January 29, 1907. Serial No. 354,735.

To all whom it may concern:

Be it known that I, CARL E. SJOMAN, a citizen of the United States, residing at Lake Park, in the county of Becker and State of Minnesota, have invented a new and useful Quick-Shifting Antirattling Thill-Coupling, of which the following is a specification.

This invention has relation to thill couplings of the character indicated and it consists in the novel construction and arrangement of its parts as hereinafter shown and described.

The object of the invention is to provide a spring for a thill coupling which is adapted to bear against the draft eye and prevent the same from rattling in the clip shackles. A lever is provided for increasing the tension of and securing said spring. A link is attached to said lever and is adapted to engage one of the clip nuts. The said link performs a double function, namely, that of connecting the lever with the clip and also for housing or protecting the free end of said lever in order that the lever may not be accidentally or unintentionally swung.

In the accompanying drawing:—Figure 1 is a side elevation of the thill coupling, and Fig. 2 is a top plan view of the same.

The coupling comprises the usual clip 1 fastening over the axle 2 and being held in place by the plate 3. Said clip is provided with the shackles 5 which receive between them the draft eye 4. The U-shaped bolt 6 has one of its legs passing through the shackles 5 and the eye 4. Said bolt is not held in position by a nut or tap as is usual but is retained in place by means which will be hereinafter explained. The spring 7 is provided with a clip 8 which receives the other leg of the bolt 6. The last said leg of the bolt lies between the upper side of the draft eye 4 and the clip 1 and the clip 8 bears directly against the side of the clip 1. The forward end of the spring 7 bears against the rear end of the draft eye 4 and has a tendency to hold the said eye 4 in a forward position with relation to the shackles 5. Consequently, rattling of the eye 4 with relation to the said shackles is prevented. The other end of the spring 7 is pivotally

attached to the lever 9 at an intermediate point thereof. The link 10 is pivoted at its upper end to the upper end of the lever 9 and the intermediate portion of the said link passes around the nut 11 on the rear clip 55 end which forms a means for fixing the lower end of the said link with relation to the clip 1. The free end 12 of the lever 9 rests against the rear side of the clip 1 when the parts are locked together and the lower 60 end of the said portion 12 of the lever 9 terminates short of the plate 3 and lies within the link 10 when the parts are locked together and thus the possibility of the said lever being accidentally or unintentionally 65 swung is reduced to a minimum and as above stated the said link serves the double purpose in that it forms the connecting means between the lever and the clip and guards the free end of said lever.

Having described my invention what I claim as new and desire to secure by Letters-Patent is:—

A thill coupling comprising a clip for attachment to an axle, a plate mounted upon the ends of the clip and lying under the axle, nuts attached to the clip ends and holding said plate in position, said clip being provided with shackles, a thill iron having an eye disposed between said shackles, a bolt 80 having parallel ends for connecting said thill iron to the clip, one end of said bolt passing through said shackles and eye and the other end having a reduced portion with shoulders at opposite ends thereof, a bifurcated lever, 85 a curved spring lying over the top of the clip and having one end engaging the eye of the thill iron and the other end formed into an eye sleeved upon a pivot mounted in the bifurcation of said lever between the 90 pivot and the other end of the lever, a clip secured to said spring and engaging the reduced portion of said coupling bolt, and a link having its ends supported in the ends of the bifurcations of said lever and its cross 95 portion engaging the inner edge of one of the nuts of the clip, said lever being shorter than the link and adapted to swing at its free end through the same and lie between the link and clip and in contact with the 100

side of the clip, said spring being of such length with relation to the lateral breadth of the clip and lying in such close proximity to the same that it must actually engage the top of the clip before the lever may move from a locked to an unlocked position.

In testimony that I claim the foregoing

as my own, I have hereto affixed my signature in the presence of two witnesses.

CARL E. SJOMAN.
